UNITED STATES PATENT OFFICE.

AUBREY F. HOFFMAN, OF LONGFORD, KANSAS.

RADIATOR-COVER.

1,352,963.

Specification of Letters Patent. Patented Sept. 14, 1920.

Application filed May 15, 1918. Serial No. 234,638.

To all whom it may concern:

Be it known that I, AUBREY F. HOFFMAN, a citizen of the United States of America, residing at Longford, in the county of Clay 5 and State of Kansas, have invented new and useful Improvements in Radiator-Covers, of which the following is a specification.

It is the primary aim and object of this invention to provide a device of the above 10 mentioned character designed to removably cover the open front end of a radiator when the vehicle is not in use so that the heat may be retained beneath the hood of the motor vehicle with a view of obviating the freez- 15 ing of the water in the radiator.

It is an equally important object of this invention to provide a device of the above mentioned character wherein the parts are capable of being adjusted to either an open 20 or closed position from a point on the dash of the vehicle and within easy reach of the driver thereof, thus obviating the necessity of the driver getting out of the vehicle to adjust the cover.

More particularly the present invention 25 includes the provision of a device of the above mentioned character wherein improved means is employed for mounting the closure curtain in advance of the open front 30 of the radiator and to also provide improved means for operating the curtain so that it may readily be placed in an open or closed position as desired.

Among the other aims and objects of this 35 invention may be recited the provision of a device of the character described with a view to compactness, and in which the number of parts are few, the construction simple and the cost of production low and the 40 efficiency high.

Other improvements and novel details in the construction and arrangement of the various parts of the apparatus will be brought out more in detail in the description 45 to follow, which for a clear understanding of the invention should be considered in connection with the accompanying drawings forming a part hereof, and wherein is disclosed for the purpose of illustration a 50 convenient and satisfactory embodiment of the invention.

Figure 1 is a front elevation of the invention applied on the front of a radiator and shown in a partly closed position.

Fig. 2 is a rear elevation of the invention proper looking toward the inside thereof.

Fig. 3 is a longitudinal sectional detail of the invention, and

Fig. 4 is a fragmentary front elevational detail of the curtains and roller.

Similar characters of reference are employed in all of the above described views to indicate corresponding parts.

Referring now, more particularly, to the accompanying drawings there is illustrated 65 a motor vehicle radiator 1, which with a dash board 2 serves to support the vehicle hood 3 in the conventional manner. Tubes 4 and 5 are extended transversely through the radiator to one side thereof and near 70 the upper and lower ends as indicated in Fig. 3 while these tubes are alined respectively with openings 6 and 7 in the dash. Extending from the dash and beneath the opening 6 and above the opening 7 are 75 brackets 8 in which are mounted idlers 9 for a purpose that will hereinafter become apparent.

With a view toward providing an improved closure means for the opening 10 in 80 front of the radiator a substantially rectangular form or casing 11 is employed the front wall thereof being provided with an opening 12, which is slightly larger than the opening 10 of the radiator, while the 85 opening 12 leaves side flanges 13 and upper and lower flanges 14 and 15, respectively, which project inwardly from the adjacent walls of the frame 11. Attaching flanges 16 extend from the side walls of the 90 frame and are secured to the front of the radiator near the side edges thereof by the instrumentality of suitable fasteners 17. Opposed trunnion brackets 18 and 19 extend inwardly from the upper 95 and lower flanges 14 and 15 respectively while an upper roller 20 and a lower roller 21 are employed and respectively have their trunnions 23 journaled in the upper brackets 18 and the lower brackets 19. A curtain 100 23 has one end secured to the lower roller and its main portion windable about the lower roller 21. A casement 24 is formed at the upper edge of the curtain and receives a cross reinforcing strip 25 while secured 105 to the respective ends of the casement are pieces of tape 26 which are also windable about the upper roller 20 and have their inner ends secured to the upper roller 20.

In this connection it is to be observed that 110 the length of the tapes 26 is equal to the length of the curtain.

In order to wind the tapes around the roller 20 so as to raise the curtain into such position as it will close the opening 12 in the frame and prevent the heated air within the hood escaping through the opening in the radiator and to also wind the curtain about the lower roller when it is desired to allow air to pass through the opening 10 in the radiator a cable 27 is employed and has one end connected to one end of the roller 20 and is windable about this end of the roller and extended through the upper sleeve 4 and the upper opening 6. This cable is now trained about the upper idler 9 and extended downwardly and trained about the lower idler 9 and thence it is passed through the lower opening 7 of the dash and thence through the lower tube or sleeve 5 in the radiator and finally is windable about one end of the lower roller 21 and has its terminal secured thereto.

In use, assuming that the parts have been assembled in the manner described and as indicated in the drawings, to raise the curtain into a closed position and to lower the curtain so that air may pass through the opening 10 of the radiator it is only necessary to engage the intermediate portion of the cable 27 and by moving it either upwardly or downwardly the rollers 20 and 21 will be actuated in corresponding directions so that the curtain will be either wound about the lower roller during which movement the tapes 26 will be unwound from the upper roller or else the tapes will be wound about the upper roller while the curtain will be unwound from the lower as is apparent. It is also to be appreciated that the cable is sufficiently taut so as to be

frictionally engaged about the idlers 9 the parts will be maintained in the adjusted positions. In actual practice, however, if desired the intermediate portion may be left slack and may be engaged on a suitable catch to insure of the parts being maintained in their proper positions.

It is believed in view of the foregoing description that a further detailed description of the invention is entirely unnecessary. Likewise it is believed that the advantages will be readily apparent.

Having thus fully described the invention what is claimed and desired to be secured by Letters Patent is:

A device for the purpose indicated comprising the combination with a vehicle radiator and dash, both of which are formed with top and bottom openings adjacent one side, of upper and lower transversely disposed rollers mounted on the front of the radiator, a curtain having one end connected to one of the rollers, operative connections between the other end of the curtain and the remaining roller, upper and lower idlers mounted adjacent corresponding openings on the dash, and a cable trained over said idlers and passing through the openings in the dash and in the radiator and having its opposite ends encircling and connecting to the upper and lower rollers, respectively, whereby movement of that section of the cable between the said idlers in one or the other direction may effect the raising or lowering of the curtain, as herein shown and for the purpose specified.

In testimony whereof I affix my signature.

AUBREY F. HOFFMAN.
